UNITED STATES PATENT OFFICE.

ALBERT G. HAMILTON, OF PITTSBURGH, PENNSYLVANIA, ASSIGNOR TO J. T. AND A. HAMILTON COMPANY, OF PITTSBURGH, PENNSYLVANIA, A CORPORATION OF PENNSYLVANIA.

DESIGN FOR A GLASS BOTTLE.

Application filed September 4, 1925. Serial No. 14,708. Term of patent 3½ years.

To all whom it may concern:

Be it known that I, ALBERT G. HAMILTON, a citizen of the United States, residing at Pittsburgh, in the county of Allegheny, State of Pennsylvania, have invented a new, original, and ornamental Design for Glass Bottles, of which the following is a specification, reference being had to the accompanying drawing, forming a part thereof.

The figure is a perspective view of a glass bottle embodying my design.

I claim:

The ornamental design for a glass bottle as shown.

ALBERT G. HAMILTON.
